(57) **CLAIM**

The ornamental design for a vertically oriented container with a lid, as shown and described.

DESCRIPTION

FIG. 1 is a front perspective view of a first embodiment of a vertically oriented container with a lid showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a front perspective view of a second embodiment of a vertically oriented container with a lid showing my new design;

FIG. 9 is a top plan view thereof;

FIG. 10 is a bottom plan view thereof;

FIG. 11 is a front elevational view thereof;

FIG. 12 is a rear elevational view thereof;

FIG. 13 is a left elevational view thereof; and,

FIG. 14 is a right elevational view thereof.

The broken lines are to show portions of the vertically oriented container with a lid, which form no part of the claimed design.

1 Claim, 8 Drawing Sheets
